UNITED STATES PATENT OFFICE.

JOHN E. DUNGAN, OF MOUNDSVILLE, WEST VIRGINIA, ASSIGNOR OF SEVEN-SIXTEENTHS TO WALTER S. ERYSON, ONE-SIXTEENTH TO BENJAMIN F. BONE, ONE-SIXTEENTH TO FRANK M. HOWARD, ONE-SIXTEENTH TO JAMES A. SCHAUER, FIVE SIXTY-FOURTHS TO ALLEN C. SCROGGINS, JR., ONE-SIXTEENTH TO H. J. ZINK, FIVE SIXTY-FOURTHS TO EDWARD EVERETT KOONTZ, ONE THIRTY-SECOND TO FLOYD H. GANDEE, ALL OF MOUNDSVILLE, WEST VIRGINIA; ONE THIRTY-SECOND TO CHALKLEY L. BUNDY, OF ADENA, OHIO; AND TWO SIXTY-FOURTHS TO WILLIAM H. HILL, OF CLEVELAND, OHIO.

CARTONING MACHINE.

Application filed October 8, 1921. Serial No. 506,310.

To all whom it may concern:

- Be it known that I, JOHN E. DUNGAN, a citizen of the United States, residing at Moundsville, in the county of Marshall and 5 State of West Virginia, have invented a new and useful Cartoning Machine, of which the following is a specification.
- This invention relates to cartoning machines for semi-solid substances such as butter, ice cream and the like and has more especial reference to a machine of this character arranged to store semi-solid substances and to automatically cut the same into blocks or prints of the desired size and shape and 10 place them in boxes or other suitable containers, the machine being so constructed and operated that the substance contained therein is not touched by the hands of the operator during the entire process.
- 15 The objects of the invention are to provide an apparatus of this character which will keep the butter, ice cream or other semi-solid substance stored therein in proper condition, and in a hardened or nearly solid state, in order that it may be easily handled; to provide means for cutting the semi-solid substance into blocks or prints of a desired 20 size and shape; to provide means for automatically placing each block or print in a separate box or container; means for moving a plurality of boxes or containers into position to be filled; means for automatically stopping the box or containers to permit the same to be filled; and means for automatically moving the box or containers 25 away from the machine after they are filled.
- Other objects of the invention are to provide means for keeping the butter or ice cream or other semi-solid substance sealed 30 from the outer air, thus preventing shrinkage of the substance; to provide means for circulating brine or cold water around the tank containing the butter or ice cream or the like, to provide means for automatically 35 operating the cut-off plate and knife which control the delivery of the semi-solid substance from the tank to the containers or boxes; and to generally improve and simplify apparatus of this character.

The above and other objects may be attained by providing a tank containing the butter, ice cream or other semi-solid substance, said tank being contained within a closed box or the like and surrounded by coils through which brine or cold water is 50 pumped, a fluid operated plunger being located within the tank, a cut-off plate and knife normally closing the mouth of the tank, in which is located a frame arranged to receive the open ends of the containers or boxes, the cut-off plate being automatically raised as each frame of empty boxes is placed in position at the mouth of the tank, allowing the fluid operated piston to force the semi-solid substance through said frame, 55 cutting the same into blocks or prints of a size adapted to easily pass into said boxes or containers, the cut-off plate and knife being automatically lowered, severing the 60 separate prints or blocks as they are conveyed into the boxes, the frame containing the filled boxes being automatically moved out of engagement with the mouth of the tank and carried away therefrom when the 65 boxes may be sealed and removed from the 70 frame.

With these objects in view, the invention consists in the construction and arrangement of parts, hereinafter described and illustrated in the accompanying drawings, 75 it being understood that various changes in the form and details of construction may be made within the scope of the appended claims.

The invention thus set forth in general 80 terms is illustrated in the accompanying drawings, in which—

Fig. 1 is a front elevation of a cartoning machine embodying the invention;

Fig. 2, a fragmentary side elevation of the 90 same, parts being broken in section for the purpose of illustration;

Fig. 3, a longitudinal sectional view through the dispensing machine;

Fig. 4, a perspective view of the tank and 95 the piping connected therewith;

Fig. 5, a plan section of the drive mechanism for the conveyor;

Fig. 6, a rear elevation of the cutting die;
Fig. 7, a section on the line VII—VII,
Fig. 6;

Fig. 8, a perspective view of a portion of
5 the piston rod of the plunger which holds
the boxes or containers in position at the
mouth of the machine;

Fig. 9, a vertical, sectional view through
10 the movable frame which carries the con-
tainers, showing the separating frame and
cutting frame;

Fig. 10, a front elevation of the separat-
ing frame;

Fig. 11, a section through the cutting and
15 separating frames on the line XI—XI,
Fig. 10;

Fig. 12, a section on the line XII—XII,
Fig. 10;

Fig. 13, a section on the line XIII—XIII,
20 Fig. 10;

Fig. 14, a section through one of the con-
tainers;

Fig. 15, an elevation of the brine or liquid
pump showing the cover plate removed;

25 Fig. 16, a section on the line XVI—XVI,
Fig. 15;

Fig. 17, an end view of one of the air
valves;

30 Fig. 18, an longitudinal section of the
same;

Fig. 19, a perspective view of the valve
plug and associated parts separated; and

Fig. 20, an end view of the valve plug.

A practical embodiment of the invention
35 is disclosed in the accompanying drawings,
forming a part of this specification, in which
similar numerals of reference indicate cor-
responding parts throughout the several
views.

40 The housing or casing of the machine is
preferably rectangular as shown in the
drawings, (see Fig. 3), and is formed of the
spaced, outer and inner walls 1 and 2, prefer-
ably formed of wood and metal respec-
45 tively, sheet cork or other insulating ma-
terial, as shown at 3 being located between
said walls, an air space 4 being preferably
provided between the walls.

50 With this construction, the interior of the
casing is efficiently insulated against heat,
preventing the surrounding atmosphere
from materially raising the temperature
within the casing.

55 A tank 5 preferably formed of sheet metal
and rectangular in cross section, is suspend-
ed within the casing thus formed, the rear
end thereof being closed and the forward
open end extending through a suitable open-
60 ing 6 provided in the forward end of the
casing.

65 A piston 7 is slidably mounted within the
tank 5 and is preferably provided with a
felt ring 8 which may be lubricated with
a fine oil, allowing the piston to move freely
within the tank, the oil also slightly lubri-

cating the inner walls of the tank, thus elim-
inating any difficulty in forcing the semi-
solid contents from the tank.

Fluid under pressure, preferably com-
pressed air, is admitted through the pipe 9,
70 a coil 10 is located around the interior of the
casing and communicates with the pipe 9,
the other extremity of said coil extending
into the rear end of the tank as at 11. It
will be understood that in the event butter
75 or the like is to be dispensed from the tank,
the lower portion of the casing is filled with
cold water, while if ice cream or similar
substance is to be dispensed, the lower por-
tion of the interior of the casing is filled
80 with brine, ice and salt being packed over
the brine in the upper portion of the casing,
over the tank and around the coil 10.

The lid 12 of the casing is formed of the
outer and inner walls 13 and 14, preferably
85 formed of wood and metal respectively, a
cork filling 15 being provided therebetween.

When the interior of the casing is filled
with brine and ice or cold water, and the lid
place in position thereon, the interior of the
casing is practically insulated against heat
and the coil 10 being passed around the in-
terior of said casing, the temperature of the
compressed air is lowered before being ad-
mitted to the tank, thus preventing any
95 melting of the ice cream or butter by con-
tact with the compressed air.

For the purpose of circulating the brine
or cold water around the tank, the pipe 16
is connected with a pump 17, the lower end
100 of said pipe extending down into the brine
or water. The pipe 18 is connected above
the pump 17 and communicates with the
coils 19 which are located around the tank
5, the opposite end of said coil forming an
105 outlet into the interior of the casing as
shown at 20.

It will be noted that the warm brine or
water which has passed through the coils
19 is returned to the casing at a point con-
siderably higher than the point where the
brine or water is drawn into the coils, thus
assuring that the coldest brine or water,
which is necessarily located in the bottom
110 of the casing, is drawn into the coils and the
warm brine or water which is discharged
from the coils is returned to the casing at
a higher point.

The pump which is provided for circulat-
ing brine or cold water is preferably of the
type shown in Fig. 15 and Fig. 16, and
comprises the casing 17 which is elliptical in
form and within which is mounted a pair
of meshing, toothed wheels 21 mounted
upon the shafts 22 which extend through
120 one side of the casing and may be rotated
in any usual and ordinary manner, the
power means not being shown.

These wheels are arranged to be driven in
the direction of the arrows shown in Fig. 130

15, the water being drawn up through the inlet opening 23 and ejected through the outlet opening 24 into the coils. It will be understood that the water or brine is carried 6 upwardly between the teeth upon the wheels, the wheels fitting snugly within the casing.

A cutting die 25 is located in the open end 10 of the tank and arranged to cut the contents thereof into a plurality of columns as it is forced from the tank through said die. This die may be designed to form these 15 columns of semi-solid material of any desired cross sectional shape, but as it is desirable in dispensing butter, ice cream and the like to form the same in rectangular bricks or prints, the die illustrated in the drawings is arranged to cut the semi-solid substance into a plurality of rectangular 20 columns.

This die is preferably provided with the spaced, vertical and horizontal blades 26, each of which is V-shaped in cross section, the sharpened edge of each blade being 25 located at the inner side of the die. The die is thus divided into a plurality of rectangular openings through each of which a column of butter, ice cream or other semi-solid substance may be forced.

30 The box separating frame 27 is slightly spaced from, and registers with the cutting die, being provided with the off-set ears 28 which register with the ears 29 upon the die, tie bolts 30 which extend to the rear end of 35 the tank being provided with the threaded extremities 31 which engage internal threads in the ears 28, thus clamping the die and separating frame tightly upon the open end of the tank.

40 This separating frame is provided with the spaced, vertical and horizontal bars 32 registering with the cutting blades 26 upon the die, each of said bars being longitudinally grooved as at 33, thus forming the rectangular flanges 34 which are of proper size 45 and shape to receive the open ends of the pasteboard boxes or containers 35.

A guide space 36 is thus provided between the die and the separating frame, through 50 which the vertically reciprocating cut-off plate 37 is mounted, the grooved guide bars 38 extending upwardly from opposite sides of the frame, forming a continuation of this guide space arranged to receive the cut-off 55 plate when the same is raised. One of the guide bars 38 is slotted as shown at 39 to permit the lateral extension 40 upon the cut-off plate to extend therethrough.

60 For the purpose of conveying empty boxes or containers to the mouth of the tank to be filled, a conveyer, preferably in the form of an endless belt 41, provided through its longitudinal center with the sprocket teeth 42, is mounted transversely across the front end 65 of the machine upon the pulleys 43 and 43^a.

The pulley 43 is rotatably mounted upon the shaft 44 which is journaled in the bearings 45. Each of said pulleys is provided with the central sockets 46 arranged to receive the sprocket teeth 42 and with the 70 slots 47 for a purpose hereinafter described. The hub 48 of the pulley 43 has fixed thereon the frusto-conical wooden block 49 provided with the tapered periphery 50 at its 75 base.

A clutch 51 provided with the oppositely flared frusto-conical flanges 52 and 53 is slidably keyed upon the shaft 44 by means of the key 54, a spring 55 located around said shaft and interposed between said clutch and the adjacent bearing 45 normally holding the conical flange 52 in frictional engagement with the wooden block 49. A drive pulley 56 is fixed upon one extremity 80 of the shaft 44 and arranged to be driven 85 from any suitable source of power.

A brake shoe 57 is carried upon the sliding rod 58 which is slidably mounted through the fixed bearing 59, a spring 60 normally holding said brake shoe out of engagement with the tapered periphery 50 of the wooden block 49. An anti-friction roller 61 is carried upon the opposite, inturned extremity of the rod 58 and engages the frusto-conical flange 52 of the sliding clutch 95 member.

For the purpose of throwing out the clutch and applying the brake upon the pulley 43, a fluid cylinder 62 is provided adjacent to said clutch, the piston rod 63 thereof 100 being provided with the inclined head 64 arranged to engage the frusto-conical flange 53 of the clutch. Pipes 65 and 66 lead to the forward and rear ends respectively of said cylinder and are connected to the valves 67 105 and 68 respectively, each of which is connected to the fluid supply pipe 69, which leads from any suitable source of fluid pressure.

Each of the valves 67 and 68, as well as 110 the other valves, which will be later described, is of the construction shown in Figs. 17 to 20 inclusive, and comprises the casing 70 having the tapered bore 71 extending longitudinally therethrough, the tapered 115 valve plug 72 being located in said bore and provided with the reduced stem 73, a washer 74 mounted upon said neck being held in engagement with the adjacent end of the casing by means of the spring 75 which engages the washer 76, a cotter pin 77 being provided for holding said washer against end movement upon the stem.

The bifurcated arm 78 is fixed upon the opposite extremity of the plug 72 and a 125 transverse bore 79 is provided through the plug arranged to register with the inlet and outlet passages 80 and 81 respectively located transversely through the casing. A longitudinal groove 82 is provided in the 130

plug 72 arranged to register with the outlet passage 81 of the casing, the plug being arranged to be turned by means of the arm 78 to alternately move the passage 79 or the groove 82 into operative position.

The arms 78^a and 78^b of the valves 67 and 68 respectively, are preferably pivotally connected by means of the link 83, the arm 78^b extending beyond the point of connection with said link into the path of the bell crank 84 and the arm 78^a of the valve 85.

The valves 85 and 86 are connected to the supply pipe 87 which leads from any suitable source of compressed fluid, said valves being connected by means of the pipes 88 and 89 with the rear and forward ends respectively of the fluid cylinder 90 which is spaced from the forward end of the tank and in alignment therewith.

20 The arm 78^c of the valve 85 is connected by means of the link 91 to the arm 78^d of the valve 86 and the extremity of the arm 78^c is connected by means of the link 92 with the slotted lever 93 pivoted at 94 upon the front wall of the casing.

30 The belt 41 is provided at spaced intervals, upon its upper surface, with the lugs 95 between which the rectangular frames 96 are arranged to be placed, each of these frames being open at its inner side and provided with the inwardly disposed flange or rib 97 around its outer side.

Each of these frames is arranged to snugly hold a plurality of pasteboard boxes 35 or containers 35 in the position best shown in Fig. 9, the open ends of these boxes being disposed toward the mouth of the tank, the boxes equaling in number the rectangular flanges 32 upon the separating frame and 40 being of suitable dimensions to receive said flanges when moved into engagement with the separating frame.

The frame 96 is provided with a longitudinally movable rear wall 98 provided with 45 perforations as at 99 and arranged to engage the inturned flange 97 when in the rearmost position. Spring fingers 100 are provided upon the outer face of the movable wall 98, these fingers being of the form best 50 illustrated in Fig. 9, extending rearwardly and toward each other as at 101, the outer free extremities thereof being curved outwardly as at 102.

The cylinder 90 is provided with a piston 55 having the elongated piston rod 103, upon the outer extremity of which is located the head 104 perforated as at 105 and provided at its periphery with the annular flange 106 arranged to engage the spring fingers 100 60 upon the movable wall 98 when the piston is in its extended position.

A pawl 107 is pivoted at its forward end as at 108 upon the piston rod 103, said pawl having the forward, vertical face 109 and 65 the rearwardly inclined face 110, a weighted

tail portion 111 extending rearwardly and being arranged to normally rest upon the pin 112 extending transversely through the adjacent side of the piston rod.

This pawl is arranged to engage the lower 70 end of the lever 113, pivoted intermediate its extremities to a stationary portion of the machine such as the bracket 114 mounted upon the cylinder 90, the upper extremity of said lever being pivotally connected by 75 means of the link 115 to the arm 78^e which is connected intermediate its extremities to the valve 116, the opposite extremity of said arm being pivotally connected by the link 117 to the arm 78^f of the valve 118.

The valves 116 and 118 are both connected to the fluid supply pipe 119, a pipe 120 connecting the valve 116 to the forward or lower end of the cylinder 121, the valve 118 being connected to the rear or upper end 85 of said cylinder by a similar pipe 122.

The cylinder 121 is provided with a piston, a piston rod 123 thereof being connected at its lower extremity to the cut-off plate 37 which is arranged to be moved vertically in 90 the guides above described by the movement of the piston within said cylinder.

A pawl 124 is pivoted at its forward end to the side of the piston rod 103 and provided with the forward, inclined face 125 95 and the rear vertical face 126, the rearwardly disposed weighted tail portion 127 thereof normally resting upon the pin 128 which protrudes from the adjacent side of the piston rod.

This pawl is arranged to engage the upper free extremity of the lever 129 which is pivoted intermediate its extremities upon the bracket 130 carried upon the cylinder 90, the lower extremity of said lever being connected by the link 131 with the bell crank 84.

The upper web of the conveyer belt 41 travels upon the horizontal platform 132 which is provided with the central longitudinal slot 133 to accommodate the sprocket 110 teeth 42 and with the longitudinal slot 134 to accommodate the depending cam lugs 135. The cam lugs 135 are arranged to be received in the slots 47 of the pulleys 43 and 44.

115 The operation of the device is as follows: the inclined head 64 being in the dotted position shown in Fig. 5, the clutch 51 will be engaged with the block 49 and the brake shoe 57 will be released therefrom, the pulley 43 being thus driven through the shaft 44 and moving the conveyer belt in the direction of the arrow shown in Fig. 1.

120 The frames 96 are filled with the empty pasteboard boxes or containers 35 and placed in succession upon the belt between the lugs 95. As each frame approaches a position opposite to the mouth of the tank, the adjacent cam lug 135 will engage the arm 78^a, 125 wiping said arm downwardly into the dotted 130

position shown in Fig. 1, throwing the valve 86 to the exhaust position and opening the valve 85, admitting air to the rear end of the cylinder 90 and starting to move the 5 piston rod 103 toward the tank, the head 104 upon said piston rod moving from the dotted position to the full line position shown in Fig. 2.

Simultaneous with this movement, the 10 downward movement of the arm 78^a to the dotted position shown in Fig. 1, will cause said arm to engage the arm 78^b, and move said arm from the dotted to the full line position shown in Fig. 1, throwing the 15 valve 67 to the exhaust position and opening the valve 68, admitting air to the rear end of the cylinder 62 and moving the piston thereof outwardly, moving the inclined head 64 from the dotted, to the full line position 20 shown in Fig. 5. This movement of the inclined head 64 will force the clutch member 51 out of engagement with the block 49 and throw the brake shoe 57 into engagement with said block, stopping the pulley 43 25 and the conveyer belt.

As the throw of the piston rod 63 is considerably less than the throw of the piston rod 103, the belt will have been stopped before the plunger head 104 engages 30 the movable wall 98 of the frame 96. As the head 104 reaches the limit of its outer movement, the boxes or containers 35 will be moved into the position shown in Fig. 9, forcing the open mouth of each box 35 around the adjacent rectangular flange 34.

As this movement of the piston rod 103 takes place, the pawl 107 will engage the lever 113, moving said lever from the dotted to the full line position as shown in Fig. 2, 40 and through the link 115 the valve 116 will be moved to the open position and the valve 118 to the exhaust position, admitting air to the lower end of the cylinder 121 and raising the cut-off plate till the lower end 45 thereof is moved out of engagement with the cutting die 25. As the cut-off plate moves upwardly, the pawl 137 will ride over the lever 93 which is then in the dotted position shown in Fig. 1.

50 As the cut-off plate is opened, the fluid pressure within the tank will move the piston 7 forwardly, discharging the contents of the tank through the open end thereof, forcing the same through the cutting die 55 and separating the butter or other semi-solid substance into a plurality of rectangular columns, corresponding substantially in size with the pasteboard containers, forcing one column into each container.

60 As the cut-off plate moves upwardly, the upper edge thereof will engage the arm 78^a, moving the same from the full line to the dotted line position shown in Fig. 2, reversing the positions of the valves 116 and 65 118, moving the valve 116 to the exhaust

position and the valve 118 to the open position, forcing the piston within the cylinder 121 downwardly and moving the cut-off plate back to the normal position, severing the columns of semi-solid substance which 70 have been forced from the tank.

With the downward movement of the cut-off plate, the pawl 137 will engage the lever 93 and move the same from the dotted back to the full line position shown in Fig. 75 1, the link 92 raising the arm 78^a and reversing the positions of the valves 85 and 86, moving the valve 85 to the exhaust position and opening the valve 86, admitting fluid to the forward or inner end of the 80 cylinder 90, forcing the piston thereof backward.

As the piston rod 103 is thus moved back to the initial position, the head 104 thereof which is frictionally held in engagement 85 with the movable wall 98, by means of the spring fingers 100, will move said wall into engagement with the flange 97 and withdraw the frame 96 from the position shown in Fig. 2, allowing the belt, which before 90 the forward movement of said piston, has been moved transversely upon the platform to the position shown in Fig. 2, to move back against the flange 136.

As the frame 96 engages the flange 136, 95 the further inward movement of the piston rod 103 will disengage the head 104 from the spring fingers 100. The pawl 124 upon the piston rod 103 will engage the lever 129 and move the same from the full line 100 to the dotted line position shown in Fig. 2 and through the link 131 and bell crank 84 will raise the arm 78^b from the full line to the dotted line position in Fig. 1, reversing the movement of the valves 67 and 68, moving the valve 68 to the exhaust position and the valve 67 to the open position, admitting fluid to the forward end of the cylinder 62 and moving the piston therein backwardly, withdrawing the inclined head 110 64 from engagement with the clutch 51, allowing the spring 55 to throw said clutch into operative position and allowing the spring 60 to release the brake shoe 57, permitting the pulley 43 to rotate with the 115 shaft 44, starting the conveyer.

The frame 96 having been moved sufficiently to clear the filled containers from engagement with the separating frame, the frame 96 containing the filled boxes, will be moved away from the mouth of the tank and is deposited upon the stationary table 138. This operation is continued as each frame 96 is moved into position adjacent to the mouth of the tank. 120

125 It will of course be understood that during the above described operation of the machine the various plug valves, which control the fluid cylinders, will remain in the positions of adjustment shown until moved 130

by the various parts of the machine which are arranged to contact therewith.

It will be evident from the above and the accompanying drawings, that a machine is thus provided which requires only the placing of the frames 96 filled with empty containers or boxes upon the conveyer belt, the entire operation of stopping the belt as the frame reaches the mouth of the tank, 10 moving the boxes into engagement with the separating frame, opening the cut-off plate, forcing the semi-solid substance through the cutting die, separating the same into a plurality of columns and forcing one column 15 into each empty box, closing the cut-off plate which severs the contents of each box, moving the filled boxes and the frame 96 out of engagement with the separating frame and starting the conveyer belt to 20 carry filled boxes away from the machine, being automatically accomplished without the necessity of any manual operation and eliminating entirely the human element.

I claim:—

- 25 1. A machine of the character described including a tank open at one end and adapted to contain semi-solid substance, a cut-off plate normally closing the open end of the tank, means within the tank for 30 automatically forcing the contents therefrom when the cut-off plate is opened, means in the open end of the tank for cutting the semi-solid substance into a plurality of columns as it is forced from the tank, means 35 for moving a plurality of containers into position to receive said columns of semi-solid substance, and means for automatically opening the cut-off plate when said containers are moved into position.
- 40 2. A machine of the character described including a tank open at one end and adapted to contain semi-solid substance, a cut-off plate normally closing the open end of the tank, means within the tank for 45 automatically forcing the contents therefrom when the cut-off plate is opened, means in the open end of the tank for cutting the semi-solid substance into a plurality of columns as it is forced from the tank, means 50 for moving a plurality of containers into position to receive said columns of semi-solid substance, and means for automatically closing the cut-off plate when said containers are filled.
- 55 3. A machine of the character described including a tank open at one end and adapted to contain semi-solid substance, a cut-off plate normally closing the open end of the tank, means within the tank for 60 automatically forcing the contents therefrom when the cut-off plate is opened, means in the open end of the tank for cutting the semi-solid substance into a plurality of columns as it is forced from the tank, means 65 for moving a plurality of containers into
- position to receive said columns of semi-solid substance, means for automatically opening the cut-off plate when said containers are moved into position, and means for automatically closing the cut-off plate 70 when said containers are filled.
4. A machine of the character described including a tank open at one end and adapted to contain semi-solid substance, a cut-off plate normally closing the open end 75 of the tank, means within the tank for automatically forcing the contents therefrom when the cut-off plate is opened, means in the open end of the tank for cutting the semi-solid substance into a plurality of columns as it is forced from the tank, means for moving a plurality of containers into position to receive said columns of semi-solid substance, means for automatically closing the cut-off plate when said containers are filled, and means for automatically moving the filled containers away from the mouth of the tank after the cut-off plate 80 has been closed.
5. A machine of the character described, including a tank open at one end and arranged to contain semi-solid substance, a cut-off plate normally closing the open end of the tank, a fluid pressure operated piston within the tank for forcing the contents 95 therefrom when the cut-off plate is open, and means for automatically closing the cut-off plate at a predetermined point in its opening movement.
6. A machine of the character described, including a tank open at one end and arranged to contain semisolid substance, a cut-off plate normally closing the open end of the tank, means within the tank controlled by the operation of the cut-off plate 100 for forcing the contents therefrom when the cut-off plate is opened, a conveyer arranged to be moved transversely across the open end of the tank and adapted to carry containers, means for automatically stopping the conveyer as each container reaches the open end of the tank, and means for automatically closing the cut-off plate at 105 a predetermined point in its opening movement.
7. A machine of the character described, including a tank open at one end and arranged to contain semi-solid substance, a cut-off plate normally closing the open end 110 of the tank, means within the tank controlled by the operation of the cut-off plate for forcing the contents therefrom when the cut-off plate is opened, a conveyer arranged to be moved transversely across the open end of the tank and adapted to carry containers, means for automatically stopping the conveyer as each container reaches the open end of the tank, means for moving each container toward the open end of the tank 115 when the conveyer is stopped, means for 120
- 125
- 130

automatically opening the cut-off plate when each container is moved toward the open end of the tank, and means for automatically closing the cut-off plate as the same reaches 5 the fully opened position.

8. A machine of the character described, including a tank open at one end and arranged to contain semi-solid substance, a cut-off plate normally closing the open end 10 of the tank, means within the tank controlled by the operation of the cut-off plate for forcing the contents therefrom when the cut-off plate is opened, means for passing containers transversely across the open 15 end of the tank, means for stopping each container in front of the tank, means for opening the cut-off plate, means for closing the cut-off plate, means for moving each container beyond the tank, and means for 20 automatically operating all of said means in the order named.

9. A machine of the character described, including a tank open at one end and arranged to contain semi-solid substance, a 25 cut-off plate normally closing the open end of the tank, means within the tank controlled by the operation of the cut-off plate for forcing the contents therefrom when the cut-off plate is opened, a conveyer arranged 30 to move containers transversely across the open end of the tank, means for stopping the conveyer as each container reaches the open end of the tank, means for opening the cut-off plate, means for closing the cut-off 35 plate, means for continuing the movement of the conveyer, and means for automatically operating all of said means in the order named.

10. A machine of the character described, 40 including a tank open at one end and arranged to contain semi-solid substance, a cut-off plate normally closing the open end of the tank, means within the tank for forcing the contents therefrom when the cut-off 45 plate is opened, a conveyer for passing containers transversely across the open end of

the tank, a fluid cylinder for stopping and starting the conveyer, a fluid cylinder for opening and closing the cut-off plate, and means upon the conveyer for operating said 50 cylinders to automatically stop the conveyer as each container registers with the open end of the tank, to open the cut-off plate after the conveyer is stopped, to close the cut-off plate as it reaches the fully opened position 55 and to start the conveyer after the cut-off plate is closed.

11. A machine of the character described, including a tank open at one end and arranged to contain semi-solid substance, a 60 cut-off plate normally closing the open end of the tank, means within the tank for forcing the contents therefrom when the cut-off plate is opened, a conveyer arranged to be moved transversely across the open end of 65 the tank, and adopted to carry containers, means for automatically stopping the conveyer as each container reaches the open end of the tank, means for shifting the conveyer transversely to move each container into 70 engagement with the open end of the tank when the conveyer is stopped, means for automatically opening the cut-off plate and means operated by the opening movement of the cut-off plate for automatically clos- 75 ing the cut-off plate.

12. A machine of the character described, including a tank open at one end and arranged to contain semi-solid substance, a cut-off plate normally closing the open end 80 of the tank, means within the tank for automatically forcing the contents therefrom when the cut-off plate is opened, a cylinder for operating the cut-off plate, a conveyer for carrying containers, a cylinder for stop- 85 ping the conveyer and means upon the conveyer for operating said cylinders as each container is moved into position at the open end of the tank.

In testimony that I claim the above, I 90 have hereunto subscribed my name.

JOHN E. DUNGAN.
